UNITED STATES PATENT OFFICE

103,225

DESIGN FOR AN ADVERTISING DEVICE

Charles Doering, Chicago, Ill.

Application September 12, 1936, Serial No. 64,832

Term of patent 14 years

To all whom it may concern:

Be it known that I, Charles Doering, a citizen of the United States and a resident of Chicago, county of Cook, and State of Illinois, have invented a new, original, and ornamental Design for Advertising Devices, of which the following is a specification, reference being had to the accompanying drawing, forming part thereof.

In the drawing:

I claim:

The ornamental design for an advertising device, substantially as shown and described.

CHARLES DOERING.
